UNITED STATES PATENT OFFICE.

EDWARD E. CLEMENT, OF WASHINGTON, DISTRICT OF COLUMBIA, ASSIGNOR, BY
MESNE ASSIGNMENTS, TO THE NORTH ELECTRIC MANUFACTURING COMPANY.

TELEPHONE-EXCHANGE SYSTEM.

Application filed December 9, 1905. Serial No. 291,097.

My invention relates to telephone exchange systems, and has for its object the production of a system wherein no operators shall be required to effect interconnection between subscribers' lines, each subscriber having means under his own control automatically to effect connection and disconnection. The system I shall hereinafter describe may be called a "full" automatic system, because the entire operation from start to finish is controlled through central office machines by subscribers.

The main distinguishing feature of the invention consists in the operation of automatic switches by means of certain relays located at the central station, the latter being designed to respond to line currents of different duration to effect the actuation of the switches.

In order to carry out my invention I make use of two wire or metallic circuits without grounds at the subscriber's station. Each subscriber signals and controls the central office apparatus merely by making and breaking the metallic circuit.

The nature of the switch controlling relays forms an important feature of my invention. These relays are of two types, the first being ordinary quick acting relays and the second sluggish or slow acting relays. It is by differentiating between short and long makes and breaks, and the consequent action or inaction of one or the other set of relays that the switches are moved and their movements directed.

The switches which I make use of in connection with the invention may be of any convenient type, but are preferably of the type which I shall hereinafter describe and shall illustrate in simplified form. It will be understood, however, that the construction of the automatic switches themselves forms no part of the present invention and will be described in detail merely for the sake of making clear the operation of the same by the co-action of the two types of relays above mentioned.

More specifically stated, my invention comprises an ordinary common battery telephone set at each subscriber's station, with a mechanical sender, or make and break device added; a pair of line-wires extending thence from the central office, where they

terminate in a first selector switch individual to the line. This selector switch has 55 vertical and rotary movements, each controlled by a working magnet, in a local circuit controlled by a suitable relay; and in order to energize these magnets as well as a suitable release magnet, in proper order, 60 through their respective circuits, I provide what I may call a distributor, consisting of a pair of sluggish relays preferably solenoids, which will respond in one direction with considerable rapidity, so as to be effectually actuated by short impulses, but which will not respond quickly in the other direction. Thus I am enabled to send groups of 65 short impulses separated by pauses of some length, during which the solenoids will have 70 time to operate, each such pause or long impulse serving to prepare the working part of the apparatus for the next series of short impulses.

No "side switches" are required in the 75 switches of the present system, the changing of the different local circuits being accomplished through relays or through the movement of the switch spindles themselves.

My invention is illustrated in the accompanying drawings, wherein—

Figure 1 is a front view of a type of automatic switch which may be employed in this system.

Figure 2 is a bottom plan view of the contact banks thereof.

Figure 3 shows a subscriber's station and the central office end of the subscriber's line.

Figure 4 shows a first selector switch.

Figure 5 shows a second selector switch.

Figure 6 shows a connector switch.

Referring to Figure 1, the switch Z has a frame 1, carrying the contact banks 2, a spindle 3, vertical magnet E, a rotary magnet D, and a release magnet W. The spindle carries the wipers 10 to co-operate with the contacts in the banks 2 and is fitted with a rotary ratchet 9 and a vertical ratchet 8, the former engaged by a pawl actuated by the magnet E, and the latter 100 actuated by a pawl under the control of the magnet D. A detent pawl 11 has two arms which engage both the rotary and vertical ratchets, and are lifted therefrom when it is desired to release the switch by means of a link 105 12 on the armature lever 14 of the release

magnet W. This magnet becoming energized pushes forward the link 12 until it engages a pin 15 on the upper or bell-crank arm of a double detent 11, and when 5 the magnet is de-energized the retracting spring 16 throws over the pawl to disengage it from the ratchets, thereby allowing the spindle to drop and rotate to its normal position. The spindle is provided with a 10 cap 22 in which is a coiled spring having one end secured to the spindle and the other to a rod 23, journalled on the spindle at one end and on a post 24 at the other. Attached to the spindle is a stop 15 arm 25. These parts operate as follows: Sliding on the post 24, the parts 23 and 25 permit vertical movement of the switch and when the spindle is down so the wipers are clear, the spring in cap 22 turns the 20 spindle around from any angular position in which it may be, to the zero position, with the stop arm 25 against the lip on the arm 23, when the detent 11 is lifted.

Figure 2 is a bottom plan view, showing 25 the switch banks 2 and the wiper arm 10. The contacts are arranged in vertical rows, forming a portion of a cylindrical surface whose axis is in the spindle.

Referring now to Figure 3, the subscriber's station A is equipped with apparatus 30 usual in common battery systems, consisting of the transmitter T, receiver R, hook H, ringers Q and condenser C. In addition to these I provide a sender O, which is a simple make and break device with one pair of springs o, o', which are normally in contact with one another. The subscriber desiring to send a number, turns the hand-wheel o³ and the pins o² then passing forwardly over the spring o' do not break its contact with spring o, but when the subscriber has set the proper number and the hand-wheel returns to its normal position 35 under the influence of a suitable tension spring, the pins o₂ passing under the spring o' while the wheel is running down, lift the spring o' from the spring o. The line-wires 2 and 3 from the subscriber's station terminate in the central office on a relay S and 40 retardation coil I. The relay S controls a pair of solenoid relays A and B. The relay S and is a quick acting relay of the ordinary form and its armatures s and s' are adapted to open and close circuits in response to the 45 energization and de-energization of the magnet.

A' and B' are the relays of the sluggish type heretofore mentioned. These relays are 50 so designed that they will pull up quickly when energized but will take some time to restore when they are de-energized. In Figure 3 I have shown the relays A' and B' as solenoids having cores a⁵ and b⁵, which are drawn up into the solenoids when the latter 55 are energized and which restore slowly be-

ing held back by the ordinary retarding means. Secured to the bottoms of the cores a⁵ and b⁵, respectively, are the insulating cam pieces a⁶ and b⁶. The cam piece b⁶ is adapted when the relay B' is de-energized to engage the spring contact b' to open the contacts b, b', and to close the contacts b² b³ b⁴. The insulating cam piece a⁶ is adapted when the relay A' is de-energized to engage the spring contact a⁴ to 70 open the contacts a³, a⁴, and when the relay A' is energized to engage the spring contact a² to momentarily close the contacts a', a² and the contacts a and a'. A battery B is provided for supplying the necessary current for the operation of the relays and for talking purposes. A retardation coil I is placed in the circuit between the battery and the telephone set, while the condensers C', C'' are inserted in the conductors 3-4 and 2-5, respectively, to prevent battery flowing to the various switches.

Referring now to Figure 4, I have therein shown a first selector switch, consisting of the following: a spindle z, on which are mounted the trunk wipers z', z² and the test wiper z³. The springs z⁴ and z⁵ are controlled mechanically by the spindle Z, and in their normal position these contacts are 90 open. The switch first making the rotary motion does not affect these springs, but upon the first vertical motion they are closed.

The spindles of the various switches are provided with one extra tooth in the vertical ratchet, thus allowing one false movement in a vertical position before bringing the wipers in position with the rows in the contact banks, that is to say, each spindle requires two vertical movements to bring its wipers in contact with the first pair of contacts. I use this false movement as a switching device for doing away with a complicated side-switch. The vertical relay S' in operating, controls the circuit of the magnet K, which causes the spindle to rotate. The relay D' controls the circuit of the test magnet F, and also in conjunction with the relay F controls the vertical magnet L to insure one full step for the spindle Z.

The relay M is simply a bridge relay which becomes energized when an idle trunk leading to a second selector switch is found, disconnects the relays S' and D' from the trunk wires 4 and 5 through the medium of the switching contacts m¹, m², m³, m⁴, m⁵, m⁶, m⁷, m⁸, controlled by its armature, thus giving a clear pair of wires for talking purposes. X is a low wound relay adapted to control a release magnet W jointly with the relays S' and D' in a manner hereinafter explained.

Referring now to Figure 5 I have shown a second selector switch which is similar to that shown in Figure 4, with the exception

of certain circuits which will be set forth in the explanation of the operation of the system.

In Figure 5 I have also shown an interrupter or circuit breaker V which is kept constantly rotating by any suitable means and connected with the vertical magnets L in Figure 4, and L' in Figure 5, and which is designed to make and break the current through these magnets and thus furnish a series of impulses for stepping up vertically the spindles of the first and second selector switches.

Referring now to Figure 6, I have shown a connector switch, which consists of a spindle Z², on which are mounted the wipers z¹⁷ and z¹⁸. The wiper z¹⁸ in this case as well as forming the sleeve side of the talking circuit, also takes the place of a test wiper, the test magnet X² being connected directly to it.

The relays S³ and D³ correspond to the relays S', S² and D', D² in the other switches. L² is the vertical magnet whose function is similar to that of L and L' in Figures 4 and 5. In addition to the set of springs controlled by the first step of the spindle Z² I have added a set of springs z¹⁹, z²⁰, z²¹, which require at least two vertical steps to be operated. Y is a ringing relay controlled by the relay M' and adapted to connect the generator G, through the medium of the contact z to furnish ringing current for the called line. The retardation coils I', I² having bridged battery between their windings, furnish talking current to the called subscriber.

The operation of this system is as follows:

Referring to Figure 3, the subscriber at station A desiring to be connected with another subscriber, first removes his receiver R, which closes the line circuit through the following path: B, 22, I, 2, H, R, T, 1, o, o', 3, S, ground to battery, and energizes the relay S, which attracts the armature s, closes the contact at s', which in turn closes the following circuit through the solenoid B', battery B, 22, conductor 22, contacts s, s', solenoid B', conductor 29, ground to battery. The core b⁵ of the solenoid B now being drawn up, battery is connected to the contacts s² of the relay S by the following path: battery B, 22, 30, b', 23, o². The relay S at this time being energized, the circuit of the solenoid A' remains open.

The subscriber at station A, after removing his receiver, sets his number-wheel o³ to the desired number, and this wheel in running down makes and breaks the contact o, o', according to the number of impulses to be sent. These makes and breaks between the contacts, o and o' affect the relay S at the central office, and this relay in turn makes and breaks its contacts. The making and breaking of the contacts s² and

s⁴ causes the solenoid A' to become energized and draw up the core a⁵. The making and breaking of the contacts s and s' keeps the solenoid B' energized, while the making and breaking of the contacts s² and s³ sends in impulses over the conductor 20, contacts b⁷, b², conductor 21, and the trunk-wire 4 to the first selector switch. These impulses of course correspond to the makes and breaks of the contacts o and o'. After this first set of impulses has been sent in, the relay S remains energized and the core a⁵ of the solenoid A' drops, and in dropping it momentarily closes together the contact springs a, a', a². This places battery on the trunk-wire 5 by the following path: ground side of battery, battery B, conductor 22, contacts s and s', conductors 24, 28, contacts a², a', conductors 27, 32, trunk-wire 5, and on the line-wire 3 as follows, ground side of battery, battery B, conductor 22, contacts s, s', conductor 28, contacts a², a', a, conductor 26, line 3. Battery being thus momentarily placed on the trunk-wire 5 operates the control relays in the various switches as described hereinafter.

Referring to Figure 4, the first set of impulses corresponding to the thousand numeral of the desired line coming in over No. 4 side of the trunk through contacts m', m, of the relay M and conductor 36, relay S', to ground, operates the relay S', which in turn closes the circuit of the rotary magnet K by the following path: ground, s⁶, s⁵, 40, f⁶, 37, K, 44, to battery B. This magnet operating a number of times corresponding to the number of impulses sent in, causes the spindle Z to rotate and bring the wipers z', z², z³, in line with the group of contacts leading to second selector switches of the desired thousand. The controlling impulse coming in over No. 5 side of the trunk through the contacts m⁴, m³ of the relay M, thence by conductor 52, relay D' to ground, operates the relay D', which in turn momentarily closes the circuit of the relay F, at the contact d', from ground d', conductor d, relay F, conductor 45, battery, ground, and this relay F operating momentarily closes the circuit of the vertical magnet L by the following path: ground, f', f², 35, d³, d², 51, to battery B. The operation of the vertical magnet L causes the spindle Z to step up vertically one step which closes the contact springs z⁴ and z⁵. It will be noticed that when the contacts d² and d³ of the relay D' are closed during the momentary impulse over wire 5, the contacts d³ and d⁴ are opened, disconnecting the constantly rotating interrupting machine V, (Figure 5), which would otherwise be connected with the vertical magnet L over the following path: ground side of battery (Figure 5), battery, V, conductor 48, thence on to conductor 48 (Figure 4) to d⁴,

115
120
125
130

d^3 , 35, L, 38, f^2 , f' and ground. This circuit being broken, as stated, at d^3 , d^4 prevents the switch from making more than one vertical movement, while the controlling impulse is coming in.

It will be noticed in the foregoing description that I have said each switch is provided with one extra tooth in the vertical ratchet to allow for one false movement before the wipers engage a contact. This false movement is not needed in the selector switches, but only in the connector switch. To make all the switches uniform, however, I provide all of them with this extra tooth, and in case of the selector switches I simply advance or step the spindle one step by a suitable setscrew. The switch frames only contain the movable parts and their operating magnets, as the relays controlling the various magnets are mounted on relay racks in dust-proof cases, as usual in standard practice. The only difference between a selector switch and a connector switch is the circuit wiring and relays. Figures 4 and 5 showing selector switches and Figure 6 showing a connector switch, as heretofore stated. This in itself, although forming no part of the present invention, is a very desirable feature, for all the actual working parts are uniform and any switch getting out of order can simply be drawn out of its case or removed from the rack and another put in its place. This avoids the necessity of having to carry in stock a certain number of first selector, second selector and connector switches for repair work.

Referring again to Figure 4, after the controlling impulse comes in and the spindle is advanced one step the wipers rest on the first contacts leading to a second selector switch of the desired thousand.

It will be obvious that upon the first vertical step of the spindle Z, the contacts z^4 , z^5 are closed. When the relay F which has been momentarily energized drops back, the relay M is then actuated, current flowing over the following path: ground side of battery, battery B, conductors 45, 47, contacts z^6 , z^4 , conductor 39, relay M, conductors 41, contacts f , f' , ground, relay F having released its armature F'. The armature of the relay M in pulling up opens the contacts $m-m'$, m^3-m^4 , m^6-m^7 , and closes the contacts $m'-m^2$, m^4-m^5 , and m^7-m^8 . The test contacts z^8 , Figure 5, upon which the wiper z^3 , Figure 4, rests, may be busy or grounded over the following path: ground side of battery, battery B, conductor 45, relay F, conductor 42, contacts m^6 , m^7 conductor 43, wiper z^3 , contact z^8 , (see Figure 5), one of the other contacts connected in multiple with z^8 , back upon a test wiper of the trunk which happens to be busy (see Figure 4 again) and to ground through the circuits of the switch of the

busy trunk which is identical with the switch shown in Figure 4 over the corresponding conductor 43, contacts m^7 , m^8 (since the corresponding relay M of the busy trunk has pulled up, closing these latter contacts) conductor 50, relay X and ground.

It will be noted that the relays F and X of the busy trunk are in series in the test circuit. The relay F of all the switches is wound to a high resistance and the relay X to a relatively low resistance. The test current is consequently cut down so that the relay X does not pull up and the busy trunk is in no wise disturbed. The relay F in this case remains energized as shown and the circuit of the vertical magnet L remains closed through the interrupting machine V, through the following path; (see Figure 5): ground side of battery, battery, interrupter V, conductor 48, conductor 48 (see Figure 4), d^4 , d^3 , conductor 35, L, 38, f'' , f' , and ground, and the switch will continue to step up vertically until an idle contact is found, that is to say one free from ground. As soon as such a contact is found, the relay F becomes de-energized by the breaking of the test circuit already traced, and the circuit of the relay M is closed by the path already traced, i. e., battery B, 45, 47, z^5 , z^4 , 39, M, 41, f , f' , to ground. The relay M now becoming energized attracts its armature, disconnects the two relays S' and D', the former by opening the contacts m , m' , and the latter by opening the contacts m^3 and m^4 , and connects the trunk-wires 4-6 and 5-7, by closing the contacts m^2-m' , m^4-m^5 , respectively, providing a continuous talking circuit from the calling subscriber to an idle second selector switch. The energization of this relay M also disconnects the relay F from the test wiper z^3 by the breaking of the contacts m^6-m^7 and in its place connects the back release relay X by the following path: z^3 , 43, m^7 , m^8 , 50, X, to ground. This relay is low-wound, as already stated, so as not to respond when the wiper of some other switch passes over a multiple of the contact upon which the test wiper z^3 rests.

The calling subscriber now being connected to a second selector switch sends in the second set of impulses which operates the second selector switch, Figure 5, in a manner identical with that of the first selector switch, Figure 4, the lines 4-6 and 5-7 being connected through the actuation of the relay M in Figure 4, as already shown. This second set of impulses operates the relay S² in Figure 5 in precisely the manner described in connection with the first set of impulses. The impulses from the relay S come over the lines 4-6, wiper z' , contact z^6 , in Figure 5, conductor 8, contacts m^{10} , m^9 , conductor 67, relay S², 130

and to ground. Relay S^2 in turn operates the rotary magnet K' , current passing from ground, contacts s^8, s^7 , conductor 71, contacts f^{10}, f^9 , conductor 59, K' , conductor 57, 5 battery, ground, causing the spindle Z' to rotate and bring the wipers z^9, z^{10} , all opposite or in line with a row of contacts leading to connector switches of a desired hundred. A controlling impulse comes in over the No. 9 side of the trunk, being sent by the closing of the circuit momentarily by the retraction of the core of the solenoid A' , in Figure 3, which closes the contacts a^2, a' , thereby sending an impulse from battery B, 10 in Figure 3, conductor 22, contacts s, s' , conductors 24, 28, contacts a^2, a' , conductor 27, conductor 32, line 5, line 5 (Figure 4), the contacts m^4-m^5 , which are now closed, line 7, wiper z^2 , contact 27 (Figure 5), line 9, 15 contacts $m^{18}-m^{12}$, conductor 68, D'' , to ground. This operates the relay D^2 , which in turn advances the switch one step, bringing the wipers to rest on the first set of contacts leading to a connector switch of the desired hundred. The spindle Z' continues to step up until the test wiper z^{11} finds an idle contact, for the reason explained in connection with the first selector switch. 20 As soon as such a contact is found the relay M^2 becomes energized and the calling subscriber is connected through to an idle connector switch of the desired hundred, and a relay X' is connected to the test wiper z^{11} . The circuits of this switch, with the exception of the back release connections, are identical with that described in connection with Figure 4, so I have not attempted to go into detail. The release circuit will be described later. 25

Referring to Figure 6, the calling subscriber now being connected to a connector switch sends in a third set of impulses which come from the relay S in Figure 3 over the conductors 4, 6, 8, 10, (the relay M^2 having operated to connect the lines 8-10 in the manner precisely the same as described for the connection of lines 4-6 by the relay M in Figure 4) wiper z^9 , contact z^{14} , line 12, conductor 81, relay S^3 , ground. 30 These impulses coming in over No. 12 side of the trunk operate the relay S^3 , which in turn closes the circuit of the rotary magnet K^2 by the following path: ground, $d^{16}, d^{17}, s^{12}, s^{11}, 91, m^{25}, m^{26}, 92, z^{23}, z^{24}, 99, K^2, 98, 94$, to battery B. This magnet K^2 operating causes the spindle Z^2 to rotate and bring the wipers z^{17}, z^{18} in line with a row containing the contacts of the desired line. 35 The controlling impulses coming in over the No. 13 side of the trunk from the momentary closure of the contacts a^2, a' of the relay A in Figure 3, and over the lines 5, 7, wiper z^2 , contact z^7 (Figure 5) conductors 9, 11, wiper z^{10} , contact z^{16} , D^3 , operates the relay D^3 , which in turn closes the circuit of the vertical magnet, L^2 by the following path: ground, $s^{18}, s^{14}, d^{16}, d^{14}, 96, z^{20}, z^{19}, 100, L^2, 98, 94$ to battery B. The operation of this magnet L^2 causes the spindle Z^2 to take one vertical step, which opens the contacts z^{24}, z^{23} , disconnecting the magnet K^2 , closing the contacts z^{22}, z^{28} , and connecting the magnet L^2 in its place. The calling subscriber now sends in the fourth set of impulses, which coming in over No. 12 side of the trunk operates the relay S^4 , which now in turn closes the circuit of the vertical magnet L^2 by the following path: ground; $d^{16}, d^{17}, s^{12}, s^{11}, 91, m^{25}, m^{26}, 92, z^{23}, 100, L^2, 98, 94$, to battery B. The operating of this magnet L^2 causes the spindle Z^2 to step up and bring the wipers to rest on the contacts of the desired line. After the first impulse of the fourth set comes in the contacts z^{19}, z^{20} are broken, removing the magnet L^2 from control of the relay D^3 and in its place connecting the relay M' by closing the contacts z^{20}, z^{21} . The controlling impulse coming in over No. 13 side of the trunk after the fourth set of impulses operates the relay D^4 , which now in turn closes the circuit of the relay M' by the following path: ground, $s^{18}, s^{14}, d^{16}, d^{14}, 96, z^{20}, z^{21}, 95, M', 88, 87, 86$, to battery B. The relay M' now becoming energized locks itself through the contacts m^{23}, m^{22} , and the wire 90 to ground through the contacts of the relays S^3 and D^3 . This controlling impulse operating the relay D^4 also momentarily places the relay X^2 in a test position by the following path: battery B, 86, $d^{18}, d^{12}, 85, X^2, 93, 19$, to wiper z^{18} . If the desired line is in use, and consequently has its circuit completed through the switch-hook H at the substation, then the circuit thus traced to wiper z^{18} would be continued through the contact at the terminal of the desired line (see Figure 3) then to the sleeve side of the line 2, through the telephone apparatus $H, R, T, 1$, contacts $o, o', 3, S$, and ground. The release relay X^2 would then draw up its armature closing the contacts x^4-x^5 , and current would flow from the battery 86, $d^{18}, d^{12}, 85, W^2$, conductor 84, contacts s^{16}, s^{17} , conductor 83, x^4, x^5 , to ground. The release magnet would restore the testing switch to its normal position. 40

In this particular case we will take it for granted that the line is not busy. The relay M' , being energized, connects the calling subscriber through to the contacts of the desired line. In addition to the relay M' connecting the talking circuit, it also opens the contacts m^{26} and m^{25} , disconnecting the vertical magnet L^2 and in its place connects the ringing relay Y by closing the contacts m^{25}, m^{24} . This ringing relay is also preferably sluggish in its action. The calling subscriber now being connected to the desired line again turns his hand-wheel sending in

an additional set of impulses, operating the relay S^3 , which now in turn operates the ringing relay Y in the following manner. When the relay S^3 pulls up, the contacts 5 s^{12} and s^{11} are closed and the following circuit is established: battery, conductors 94, 98, relay Y , conductor 97, contacts m^{24} , m^{25} , conductors 91, 89, contacts s^{11} , s^{12} , d^{17} , d^{16} , ground. This ringing relay in operating 10 disconnects the calling end of the trunk and connects generator current to the called end notifying the desired subscriber that he is wanted. The called subscriber is supplied with current for talking through the two 15 retardation coils I' , I'' , by the following path: to battery, conductors 86, 87, I'' , 102, 15, m^{20} , m^{21} , 16, 19, sleeve wiper z^{18} , subscriber's circuit, tip wiper z^{17} , conductors 18, 17, contacts m^{19} , m^{18} , conductors 14, 101, I' , 20 D^{16} , ground.

At the end of the conversation the calling subscriber upon hanging up his telephone, effects the release of the various switches in the following manner:

25 During conversation the core of the solenoid B' remains drawn up, while that of solenoid A' remains down. The calling subscriber upon hanging up his telephone opens the line-circuit, deenergizing the relay S , whereupon the solenoid A' at once draws up 30 its core a^5 , while the core b^5 of the solenoid B' begins to drop, and as soon as it assumes its normal position battery is connected to both sides of the trunk by the following 35 path: battery B , a^4 , a^3 , b^4 , b^3 , b^2 , 21, 31. After it has assumed its normal position, the contacts b , b' are broken, opening the circuit of the solenoid A' whose core a^5 thereupon begins to drop, and as soon as it assumes its 40 normal position the contacts a^3 , a^4 , are broken and battery is removed from the trunk-wires 4 and 5, respectively. It will be seen from this method of operation that the joint action of these solenoids places battery momentarily on both sides of the trunk for 45 releasing.

50 Referring now to Figure 6, this momentary impulse coming in over both sides of the trunk operates the relays S^3 and D^3 , simultaneously, which closes the circuit of the release magnet W^2 by the following path: battery B , 86, d^{18} , d^{12} , 85, W^2 , 84, s^{16} , s^{15} , S^2 , s^{10} , and in Figure 5, z^{11} , 63, m^{16} , m^{17} , X' to ground. The operation of magnet W^2 restores the switch to its normal position. The simultaneous operation of the relays S^3 and D^3 also releases the locking relay M' by removing ground from the contact m^{22} . In 55 Figure 5 the relay X' being in series with the magnet W^2 , Figure 6, as already described, also becomes energized and attracting its armature closes the circuit of the release magnet W' by the following path: battery B , W' , x^3 , x^2 , 66, z^8 , and in Figure 4, z^2 , 43, m^7 , m^8 , 50, X to ground. The opera-

tion of the release magnet W' restores the second selector switch to its normal position and the spindle Z' coming to rest opens the contacts z^{12} , z^{13} and releases the relay M^2 . The relay X , Figure 4, being in series with the magnet W' , Figure 5, also becomes energized and attracting its armature closes the circuit of the release magnet W by the following path: ground, x' , x , W , 49, to battery B . The operation of this magnet restores the first selector switch to its normal position, and the spindle Z coming to rest opens the contacts z^4 , z^5 , releasing the relay M .

80 It will be seen from the description of the foregoing circuit that the releasing of the various switches is controlled directly from the distributor of the calling subscriber and not as ordinarily from the connector switch. In place of sending an impulse over both sides of the trunk for releasing, I may operate the release magnets directly by the two solenoids, in various ways.

Having thus described my invention what I claim is:

1. In an automatic telephone exchange system a plurality of subscribers' stations and metallic circuit lines extending thence to a central office, automatic switching apparatus for interconnecting the lines at the central office, a source of current connected in the metallic circuit of a subscriber's line, means at the substation to make and break the said metallic circuit at will, the makes and the breaks being of varying but predetermined duration, and means at the central office responsive to such makes and breaks in the metallic circuit to actuate, control and release the automatic switching apparatus and also to ring the wanted subscriber, substantially as described.

2. In a telephone exchange system a plurality of subscribers' stations and metallic circuit lines extending therefrom to a central office, automatic switching apparatus having one or more actuating magnets and release magnets, and a common source of current supply for the lines at the central office, a telephone at each substation adapted to be bridged across the metallic circuit and to derive current therefrom for talking purposes, and means at each substation to make and break the metallic circuit in accordance with any desired or necessary code signal, together with means at the central office responding to the makes and breaks of the metallic circuit and adapted to actuate the automatic switching apparatus, to shift the control of the actuating means to that end as required, to ring the wanted subscriber, and finally to release and clear out the apparatus, substantially as described.

3. In a telephone exchange system a plurality of subscribers' stations and metallic circuit lines extending therefrom to a cen-

- tral office, automatic switching apparatus having one or more actuating magnets and release magnets, and a common source of current supply for the lines at the central office, a telephone at each substation adapted to be bridged across the metallic circuit and to derive current therefrom for talking purposes, and means at each substation to make and break the metallic circuit in accordance with any desired or necessary code signal, together with means associated with each line at the central office responding to the makes and breaks of the metallic circuit and adapted to actuate the automatic switching apparatus, to shift the control of the actuating means to that end as required, to ring the wanted subscriber, and finally to release and clear out the apparatus, substantially as desired.
4. In a telephone exchange system a plurality of subscribers' lines and line-circuits extending therefrom to a central office, a first selector switch associated with each line at the central office, auxiliary switches in groups accessible from said first selector switches and serving to trunk a calling line through selected groups of switches to the line wanted, means at each substation for making and breaking the line-circuit, and relays associated with each line and connected therewith between the substation and the first selector switch, said relays responsive to the makes and breaks in the line-circuit and controlling the local circuits of the first selector switch and through it when in use controlling the circuits of selected auxiliary switches, all substantially as described.
5. In a telephone exchange system a plurality of subscribers' lines and metallic talking circuits extending therefrom to a central office, a first selector switch associated with each line at the central office, auxiliary switches in groups accessible from said first selector switches and serving to trunk a calling line through selected groups of switches to the line wanted, means at each substation for making and breaking the talking circuits, and relays associated with each line and connected therewith between the substation and the first selector switch, said relays responsive to the makes and breaks in the line-circuit and controlling the local circuits of the first selector switch and through it when in use controlling the circuits of selected auxiliary switches, all substantially as described.
6. In an automatic telephone exchange system, a subscriber's station and a central office with a metallic line circuit interconnecting them, automatic switching apparatus at the central office, and means for making and breaking the metallic circuit at the subscribers' station, means connected to the subscriber's metallic talking circuit and becoming active upon the closure of the same at the subscriber's station, for placing the automatic switching apparatus under operative control of the line, means responsive to makes and breaks only in the talking circuit to actuate said switching apparatus, to shift the control of the same, and to ring the wanted subscriber when selected; and means responsive to a final and continued break in the talking circuit to restore said switching apparatus to its normal position and render it inactive as long as the line-circuit remains broken, substantially as described.
7. In an automatic telephone exchange system a plurality of subscribers' stations and a central office, with two-wire line-circuits interconnecting them, a series of automatic switches for interconnecting the lines, means at each sub-station for producing current changes in the two wires of its line, means at the central office responsive to such changes to actuate one or more of said automatic switches, successively, so as to build up a link connection with a line wanted, and means controlled by the calling subscriber over his line for restoring the first of said automatic switches and through the same for restoring the successive links by sending forward the necessary impulses therethrough, substantially as described.
8. In an automatic telephone exchange system, subscribers' two-wire lines with substation controlling apparatus, and central office automatic switches, each switch comprising an actuating member or spindle, contact devices moved thereby to effect the desired connection, and controlling devices for said switch comprising magnets and relays only, separate local circuits for the several magnets, adapted to be selectively energized, to produce the proper movements of the contact devices, a switch circuit constituting a continuation of the subscriber's line circuit, and relays responsive to current in said circuit and adapted to vary the connections in the local circuits so as to selectively shift the control thereof as and for the purpose stated, substantially as described.
9. In a telephone exchange system, a subscriber's metallic two-wire line circuit, an automatic switching set comprising blanks of resting contacts arranged in a plurality of rows, co-operating active or movable contacts having motion in two directions for effecting connection with the bank contacts, working magnets for actuating the movable contacts in each direction, means responsive to changes in the subscriber's metallic circuit for energizing said magnets, and controlling relays also responsive to changes in the metallic circuit and adapted to shift the cir-

cuits of the working magnets, whereby no mechanical side switches are required, substantially as described.

10. In an automatic telephone exchange system, a plurality of subscribers' metallic circuit lines without grounds, a telephone talking set at each substation, and a signaling device also at each substation for making and breaking the metallic circuit, a relay connected with the line at the central office, and a source of current for the line, together with a pair of branch circuits controlled by said relay, one branch being closed when the relay is energized and the other when it is deenergized, a pair of sluggish relays in said branches, adapted to pull up their armatures but not to retract the same on short current changes, automatic switches for interconnecting the lines, with actuating and release circuits for said switches under the control of said sluggish relays, substantially as described.

11. In a telephone exchange system, a line circuit and automatic switches for connecting the same with other circuits, a relay responsive to all changes in the line and having front and back contacts, with a pair of sluggish relays connected to said contacts respectively, and controlling circuits for said switches jointly controlled by said relays, substantially as described.

12. In a telephone exchange system, line circuits, and automatic switches for interconnecting them, with means for controlling said automatic switches comprising a fast relay responsive to line current, and a pair of slow relays, said fast relay having contacts adapted when it is vibrating to energize both slow relays, when it remains attracted to energize one slow relay only and when it is retracted to energize the other slow relay only, substantially as described.

13. In a telephone exchange system, metallic line circuits, automatic switches for interconnecting the same, and means for controlling said switches comprising a fast relay and a pair of sluggish relays controlled thereby, for each line, together with local actuating and release circuits extending from said relays to said switches, substantially as described.

14. The combination of a line circuit, a source of current connected thereto, means for establishing in said circuit either a continuous or a rapidly interrupted current from said source, with a line relay acting quickly both on makes and breaks, front and back contacts closed by said relay when energized and deenergized respectively, an auxiliary relay connected to each of said contacts, each of said auxiliary relays adapted to pull up its armature or core quickly, but to release the same slowly, automatic switches, and controlling circuits therefor passing through contacts on the

sluggish relays and controlled therethrough by the quick relay, substantially as described.

15. In a telephone exchange system, automatic switches, and controlling means therefor comprising a quick acting relay and a pair of solenoids controlled by said quick acting relay, said solenoids acting quickly upon energization but slowly upon de-energization, substantially as described. 70 75

16. In a telephone exchange system, a subscriber's station, a line circuit extending to a central office, a line relay at said office, automatic switching devices actuated, shifted, controlled, and released, and ringing means also actuated through the line by said relay, substantially as described. 80

17. A telephone exchange system comprising a subscriber's station having a transmitter, receiver, call-bell and call transmitting device, a two-conductor circuit extending from said station, a plurality of interconnecting link-circuits, other subscribers' lines, associated automatic step-by-step switch mechanism for selectively extending the two-conductor circuit through said link-circuits to said other subscribers' lines, means for advancing and releasing said mechanism by variations of current transmitted over said two-conductor circuit, means whereby conversation may be held over said circuit, and means for actuating said call-bell by current over said circuit. 90 95

18. A telephone exchange system comprising a subscriber's station having a transmitter, receiver, call-bell, and call transmitting device, a two-conductor circuit extending from said station, interconnection link-circuits, other subscriber's lines, automatic step-by-step switch mechanism for selectively extending said two-conductor circuit through said link-circuits, to said other subscribers' lines, a central source of current, means for advancing and releasing said mechanism by variations in said two-conductor circuit of current derived from said source, means for energizing said transmitter over said circuit from said source, and means for actuating said call-bell by current over said circuit. 100 105 110 115

19. A telephone exchange system comprising a two-conductor circuit, associated automatic step-by-step switch mechanism having waiting contacts divided into groups and a co-operating moving contact, and means responsive to variations of current transmitted over said circuit to advance said moving contact both to a desired group of waiting contacts and then to a desired contact in that group. 120 125

20. A telephone exchange system comprising a two-conductor circuit, associated automatic step-by-step switch mechanism having waiting contacts divided into groups and a co-operating moving contact, means 130

responsive to variations of current transmitted over said circuit to advance said moving contact both to a desired group of waiting contacts and then to a desired contact in that group, and means responsive to a change in the current condition in said circuit to bring said moving contact to its normal position.

21. A telephone exchange system comprising a two-conductor circuit, associated automatic switch mechanism having waiting contacts divided into group and a co-operating moving contact, means outside of said mechanism for rendering some of said waiting contacts busy, means for advancing said moving contact to a desired group of waiting contacts in response to variations of current transmitted over said circuit, means for starting said moving contact in search of an idle contact in that group in response to another current variation in said circuit of a different character, and means for continuing the movement of the moving contact in such search and stopping it only when an idle waiting contact is found.

22. A telephone exchange system comprising a two-conductor circuit, associated automatic switch mechanism having waiting contacts divided into groups and co-operating moving contact, means outside of said mechanism for rendering some of said waiting contacts busy, means for advancing said moving contact to a desired group of waiting contacts in response to variations of current transmitted over said circuit, means for starting said moving contact in search of an idle contact in that group in response to another current variation transmitted over said circuit, and means for continuing the movement of said moving contact in such search and stopping it only when an idle waiting contact is reached.

23. A telephone exchange system comprising a control circuit associated automatic switch mechanism having waiting contacts divided into groups and a co-operating moving contact, a primary magnet and associated means for stepping said moving contact to a desired group of waiting contacts, a secondary magnet and associated means for stepping said moving contact to a desired contact in that group, a sluggish relay for controlling the operating circuit of said secondary magnet, a quick-acting relay for controlling said primary magnet and said sluggish relay, means for energizing and de-energizing said quick-acting relay by making and breaking said control circuit to operate said primary stepping magnet and energize and maintain said sluggish relay energized during such operation and then to de-energize said sluggish relay to operate said secondary magnet.

24. A telephone exchange system comprising

ing a control circuit, associated automatic switching means having waiting contacts divided into groups and a co-operating waiting contact, primary means for stepping said moving contact to a desired group of waiting contacts, secondary means for stepping said moving contact to a desired waiting contact in that group, and quick and sluggish relays controlled over said control circuit, the former to cause the operation of said primary means and the latter to initiate the operation of said secondary means.

25. A telephone exchange system comprising a subscriber's station having a transmitter, receiver, call bell, and call transmitting device, a two-conductor circuit extending from said station, a plurality of interconnecting link circuits, other subscribers' lines, associated automatic step-by-step switch mechanism for selectively extending the two-conductor circuit through said link-circuits to said other subscribers' lines, means for advancing said mechanism in response to current variations transmitted over said two-conductor circuit, means for releasing said mechanism by opening said circuit, means for holding conversation over said circuit, and means for actuating said call bell by current over said circuit.

26. A telephone exchange system comprising a two-conductor telephone circuit, associated automatic switch mechanism having waiting contacts divided into groups and a cooperating moving contact, means outside of said mechanism for rendering some of said waiting contacts busy, means for advancing said moving contact to a desired group of waiting contacts in response to successive intermittent current variations transmitted over the two talking conductors of said circuit, means for starting said moving contact in search of an idle contact in that group, and means for continuing the movement of said moving contact in such search and stopping it only when an idle waiting contact is reached.

27. A telephone exchange system comprising a two-conductor circuit, associated automatic switch mechanism having waiting contacts divided into groups and a cooperating movable contact, means outside of said mechanism for rendering some of said waiting contacts busy, a primary electromagnet, a secondary electromagnet, means for causing interruptions of said two-conductor circuit, whereby said electromagnets step said movable contact to a desired group and then to an idle waiting contact in the group, and means for causing rotation of said switch mechanism responsive to a further interruption of said two-conductor circuit.

28. In a telephone system, the combination of a line, a plurality of electrically-propelled

- and step-by-step actuated switches, connections between said switches, line circuits for successively controlling said switches, a subscriber's device for intermittently closing the line to establish said circuits, each line circuit including the two sides of the line in series, and means for supplying current over the line to operate said switches, and for talking purposes also.
29. In a telephone exchange system, the combination of telephone lines, automatic connectors less in number than said telephone lines, selectors less in number than the telephone lines, subscribers' individual switches corresponding in number to the telephone lines, subscribers' devices for closing the lines to control said individual switches and selectors and connectors by transmitting a varying number of impulses for each digit of the called number, line circuits by which the said individual switches and selectors and connectors are controlled, each line circuit including the two sides of a calling telephone line in series, means for releasing said individual switches and selectors and connectors by the opening of the calling line, and means for supplying current over the telephone lines to operate said connectors and selectors and individual switches, and for talking purposes also.
30. In a telephone system, the combination of a calling telephone line, a called telephone line, automatic step-by-step switches for trunking the calling line into connection with the called line by the automatic selection of trunks in predetermined groups, means for opening the calling line to release or restore the said switches, the said switches provided with release mechanism responsive to the opening of the calling line to release the switches either before or after the called subscriber answers, and means for supplying current over the telephone lines to operate said switches, and for talking purposes also.
31. In a telephone system, the combination of telephone lines, trunk-lines, automatic self-contained step-by-step operated trunk selectors for selecting idle trunk-lines, automatic self-contained step-by-step operated connectors for completing connection with the called telephone lines, line circuits for controlling said selectors and connectors, said line circuits each including the two sides of a calling telephone line in series, and means for supplying current over the telephone lines to operate said selectors and connectors, and for talking purposes also.
32. In a telephone system, the combination of a plurality of switches each adapted to both vertical and rotary step-by-step motion in response to one or more impulses for the called number, telephone lines, line circuits for successively controlling the said switches to extend connection from a calling line to a called line, said line circuits each including the two sides of the calling lines in series, and means for supplying current over the telephone lines to operate said switches, and for talking purposes also.
33. In a telephone system, the combination of a plurality of automatic switches, telephone lines, line circuits for successively controlling said switches to extend connection from a calling line to a called line by the transmission of a varying number of impulses for each digit of the called number, means for opening the lines when the subscribers hang up their telephones, means directly responsive to the opening of a connected telephone line for initiating the release of all switches between the lines of calling and called subscribers, and means for supplying current over the telephone lines to operate said switches, and for talking purposes also.
34. In a telephone system, the combination of trunk lines, an automatic step-by-step trunking switch provided with trunk-selecting mechanism, and with releasing mechanism, a telephone line, a subscriber's releasing device for said telephone line, line circuits for controlling the operation of said switch, said circuits each including the two sides of the telephone line in series, the release mechanism of said switch being directly responsive to a subscriber's releasing device, and means for supplying current over the telephone line to operate said switch, and for talking purposes also.
35. In a telephone system free from operating grounds at the substations thereof, the combination of telephone lines, automatic trunking and connecting switches, line circuits by which a calling subscriber successively controls a plurality of said switches to extend connection to the called subscriber's line by the transmission of a varying number of impulses for each digit of the called number, said circuits each including the two sides of a calling telephone line in series, subscribers' releasing devices for the telephone lines, means immediately responsive to said releasing devices for releasing or restoring said switches to normal condition, and means for supplying current over the telephone lines to operate said switches, and for talking purposes also.
36. In a telephone system free from operating grounds at the substations thereof, the combination of telephone lines, automatic switches, line circuits for successively controlling a plurality of said switches to extend connection to a called subscriber's line, by the transmission of a varying number of impulses for each digit of the called number, means for transmitting impulses over said circuits, said line circuits each includ-

- ing the two sides of a calling telephone line in series, each switch provided with a switch shaft adapted for both vertical and rotary motion, means carried by the shaft of each 5 switch for extending connection in the direction of the called subscriber, and means for supplying current over the telephone lines to operate said switches, and for talking purposes also.
- 10 37. In a telephone system, a subscriber's station, a step-by-step vertical and rotary switch allotted to said station, means whereby the said switch may be released at any stage of the call, by simply breaking or 15 opening the line circuit, and means for supplying operating and talking current from the central station, substantially as set forth.
38. In a telephone system, a called line, a connector provided with an element having 20 vertical and rotary step-by-step motion to find the called line, release mechanism for restoring the connector to normal position, and a single line relay operative to control the vertical and rotary motion and the re- 25 lease of said connector.
39. In a telephone system, a called line, a connector provided with line wipers having vertical and rotary step-by-step motion to find the called line, and a single line relay operative to control the vertical and rotary motion.
40. In a telephone system, the combination 35 of a called line, a connector provided with an element having vertical and rotary step- by-step motion to find the called line, release mechanism for restoring the connector to normal position, a single line relay operative to control the vertical and rotary motion and the release of said connector, and means 40 for controlling said relay over a metallic line circuit.
41. In a telephone system, the combination 45 of a called line, a connector provided with line wipers having vertical and rotary step- by-step motion to find the called line, a single line relay operative to control the vertical and rotary motion, and means for controlling said relay over a metallic line circuit.
- 50 42. In a telephone system, the combination of a connector provided with an element having vertical and rotary motion to find the called line, release mechanism for restoring the connector to normal position, a single 55 line relay operative to control the vertical and rotary motion and the release of said connector, and a calling mechanism to which said relay is responsive, said mechanism requiring a separate manual adjustment there- 60 of for each digit of the called number, adapted to transmit suitable current for one digit before adjustment thereof for the next digit.
43. In a telephone system, the combination 65 of a connector provided with line wipers having vertical and rotary motion to find the called line, a single line relay operative to control the vertical and rotary motion, and means for supplying current over the telephone lines to operate said switches, and for talking purposes also.
44. In a telephone system, the combination 75 of a metallic line circuit, a connector provided with an element having vertical and rotary motion to find the called line, release mechanism for restoring the connector to normal position, a single line relay operative to control the vertical and rotary motion and the release of said connector, and means for controlling said relay over said metallic line circuit, comprising a calling mechanism to which said relay is responsive, said mechanism requiring a separate manual adjustment there- 80 of for each digit of the called number, adapted to transmit suitable current for one digit before adjustment thereof for the next digit.
45. In a telephone system, the combination 85 of a metallic line circuit, a connector provided with line wipers having vertical and rotary motion to find the called line, a single line relay operative to control the vertical and rotary motion, and means for controlling said relay over said metallic line circuit, comprising a calling mechanism to which said relay is responsive, said mechanism requiring a separate manual adjustment there- 90 of for each digit of the called number, adapted to transmit suitable current for one digit before adjustment thereof for the next digit.
46. A telephone exchange system comprising 95 a two-conductor circuit, associated automatic switch mechanism having waiting contacts divided into groups and a cooperating moving contact, means outside of said mechanism for rendering some of said waiting contacts busy, means for advancing said moving contact to a desired group of waiting contacts in response to a variation of current transmitted over said circuit, means for starting said moving contact in search 100 of an idle contact in that group in response to another current variation transmitted over said circuit, and means for continuing the movement of said moving contact in such search and stopping it only when an idle waiting contact is reached.
47. A telephone exchange system comprising 110 a telephone line extending from a central office to a distant point, a source of current in circuit with said line, normally controlled means at said distant point for interrupting the circuit of the line, other telephone lines, an electrically controlled switch at the central office for establishing connection between said line and said other lines, active 115 contacts for said switch constituting termi- 120
- 125
- 130

nals for said line, passive contacts for said switch constituting terminals for said other lines, restoring means for said switch, means responsive to short making and breaking 5 of the circuit of said line for causing a primary operation of said switch, and means responsive after connection is established with a desired line whereby a long interruption of the circuit of said line will cause a 10 secondary operation of said switch.

48. A telephone exchange system comprising a two-conductor telephone circuit, associated automatic switch mechanism having waiting contacts divided into groups and a 15 cooperating moving contact, means outside of said mechanism for rendering some of said waiting contacts busy, means for advancing said moving contact to a desired group of waiting contacts in response to 20 current variation transmitted over the two talking conductors of said circuit in series, means for starting said moving contact in search of an idle contact in that group, and means for continuing the movement of said 25 moving contact in such search and stopping it only when an idle waiting contact is reached.

49. In a telephone system, the combination 30 with an automatic switch provided with operating and restoring magnets, of a closed controlling circuit for said switch, means for causing interruptions of said circuit, a plurality of quick acting relays responsive to said interruptions, and circuits 35 for said magnets controlled by said relays.

50. In a telephone system, the combination 40 with a metallic line circuit extending to a central exchange and means for transmitting current impulses over the two sides thereof in series, of a progressively movable switching mechanism provided with a plurality of motor magnets, and a plurality of quick acting relays in said switch responsive to 45 said current impulses for controlling said magnets.

51. In a telephone system, the combination 50 with a metallic line circuit extending to a central exchange and means for transmitting current impulses over the two sides thereof in series, of a progressively movable switching mechanism provided with a plurality of motor magnets, and a plurality of relays in said switch for controlling said magnets, each of said relays responsive to each of said 55 impulses.

52. In a telephone system, the combination 60 with a metallic line circuit and means for transmitting current impulses over the two sides thereof in series, of an automatic selector switch having primary and secondary selecting functions, primary and secondary motor magnets for operating said switch to perform said functions, and a plurality of relays for controlling said magnets, said re-

lays each responsive to each of said impulses. 65

53. In a telephone system, the combination with an automatic switch having operating and restoring magnets, of a controlling circuit for said switch, means for causing short or long interruptions in said circuit, and 70 a plurality of relays each responsive to interruptions of both kinds for controlling said magnets.

54. In a telephone system, the combination with an automatic switch and a controlling 75 circuit therefor, of means for producing current impulses in said circuit, operating magnets in said switch responsive to said impulses, switching means for controlling the circuits of said operating magnets, and a 80 pair of relays responsive to said impulses for controlling said switching means.

55. In an exchange system, the combination with a plurality of metallic line circuits extending from substations to a central 85 office, of a plurality of line selectors at the central office switch mechanism at each substation adapted to produce current variations in the line circuit thereof, and means at the central office responsive to said variations adapted to cause a series of said 90 selectors operating in succession to connect said metallic line circuit with another for telephonic communication.

56. In a telephone exchange system, the combination with a plurality of line circuits, each comprising two conductors extending from a substation to a central office, of group and individual line selectors at the 95 central office, switch mechanism at each substation adapted to produce current variations in the line circuit thereof, and means at the central office responsive to said current variations to cause a series of said 100 selectors operating in succession to connect said line circuit with another for telephonic communication.

57. In a telephone exchange system, the combination with subscribers' line circuits, 110 each comprising two conductors extending from the substation thereof to a central office, of switch mechanism at each substation for producing current variations in the line circuit thereof, and a series of selectors at the central office operating in succession in response to said current variations and adapted thereby to interconnect such line circuit with another for telephonic communication.

58. In a telephone exchange system, the combination with a plurality of metallic line circuits, of means for producing current variations in said circuits, a group selector switch and a line connector switch, said switches being adapted to operate in succession in response to such current variations to interconnect the said circuits for telephonic communication. 125

59. In a telephone exchange system, the combination with a plurality of subscribers' lines, each comprising the two conductors of a metallic circuit, of means for producing current variations in successive periods in said circuit conductors, group selector switches and line connector switches associated with said lines, said switches being adapted to operate one after another during such successive periods in response to said current variations to interconnect said line circuits for telephonic communication. 65
60. In a telephone exchange system, the combination with a plurality of subscribers' line circuits each comprising two conductors without ground connections at the substation thereof, of a switch mechanism at each substation adapted to cause current variations in a circuit including two line conductors thereof, and a series of automatic switch mechanisms operating in succession in response to said current variations and adapted thereby to connect said line conductors with the corresponding conductors of another line for telephonic communication. 70
61. In a telephone exchange system, the combination with a plurality of metallic line circuits free from operative grounds outside of the central office, of means for producing current variations in any one of said circuits, and a plurality of automatic switches adapted to operate in succession in response to such current variations to connect one of said metallic line circuits with another for telephonic communication. 75
62. In an automatic telephone exchange system, the combination of a calling telephone line, a called telephone line, a series of automatic switches for extending connection from the calling line to the called line, a plurality of line circuits by which said switches are successively controlled, each said line circuit including the two sides of calling line in series, and means for supplying current over the telephone lines to operate said switches, and for talking purposes also. 80
63. In a telephone exchange system, the combination of a calling telephone line, a called telephone line, a series of automatic switches for extending connection from the calling line to the called line, means for opening the calling line to release said switches, means for releasing said switches by the opening of said line, and means for supplying current over the telephone lines to operate said switches, and for talking purposes also. 85
64. In a telephone exchange system, the combination of a subscriber's telephone line, an automatic switch, a rotatable calling device adapted by its backward rotation to intermittently close together the two sides of the telephone line, means in said switch for responding to the intermittent closing of the line, means for restoring the switch to normal position by opening the line, and means for supplying current over the subscriber's telephone line to operate said switch, and for talking purposes also. 90
65. In a telephone system, the combination of a calling telephone line, a called telephone line, automatic switches for trunking the calling line into connection with the called line, means for opening the calling line to release or restore the said switches, the said switches provided with release mechanism responsive to the opening of the calling line to release the switches either before or after the called subscriber answers, and means for supplying current over the telephone lines to operate said switches, and for talking purposes also. 95
66. In a telephone system, the combination of telephone lines, trunk-lines, automatic self-contained trunk selectors for selecting idle trunk-lines, automatic self-contained connectors for completing connection with the called telephone lines, line circuit for controlling said selectors and connectors, said line circuits each including the two sides of a calling telephone line in series, and means for supplying current over the telephone lines to operate said selectors and connectors, and for talking purposes also. 100
67. In a telephone system, the combination of a plurality of switches, each adapted for both primary and secondary motion, telephone lines, line circuits for successively controlling the said switches to extend connection from a calling line to a called line, said line circuits each including the two sides of the calling line in series, and means for supplying current over the telephone lines, to operate said switches, and for talking purposes also. 105
68. In a telephone system, the combination of a plurality of automatic switches, telephone lines, line circuits for successively controlling said switches to extend connection from a calling line to a called line, means for opening the lines when the subscribers hang up their telephones, means directly responsive to the opening of a connected telephone line for initiating the release of all switches between the lines of calling and called subscribers, and means for supplying current over the telephone lines to operate said switches, and for talking purposes also. 110
69. In a telephone system, the combination of a plurality of switches, telephone lines, line circuits for successively controlling said switches to extend connection from a calling line to a called line, said circuits each including the two sides of a calling telephone line in series, a subscriber's releasing 115
70. In a telephone system, the combination of a plurality of switches, telephone lines, line circuits for successively controlling said switches to extend connection from a calling line to a called line, said circuits each including the two sides of a calling telephone line in series, a subscriber's releasing 120
71. In a telephone system, the combination of a plurality of switches, telephone lines, line circuits for successively controlling said switches to extend connection from a calling line to a called line, said circuits each including the two sides of a calling telephone line in series, a subscriber's releasing 125

device for each line, each of said switches being provided with a release mechanism directly responsive to any subscriber's releasing device, and means for supplying current over the telephone lines to operate said switches, and for talking purposes also.

70. In a telephone system free from operating grounds at the substation thereof, the combination of telephone lines, automatic switches, line circuits for successively controlling a plurality of said switches to extend connection to a called subscriber's line, said line circuits each including the two sides of a calling telephone line in series, each switch provided with a switch shaft adapted for both primary and secondary motion, means carried by the shaft of each switch for extending connection in the direction of the called subscriber, and means for supplying current over the telephone lines to operate said switches, and for talking purposes also.

71. In an automatic common battery telephone system, the combination of a calling line and a called line, a series of switches for trunking the calling line into connection with the called line, means whereby the calling subscriber may break the connection and restore said switches by simply separating his line conductors, and means for supplying operating and talking current from the central station, substantially as set forth.

72. In a telephone system, the combination of a calling line and a called line, a series of switches for trunking the calling line into connection with the called line, means whereby the calling subscriber may release the switches, either before or after the called subscriber answers, by simply opening up his line, and means for supplying operating and talking current from the central station, substantially as set forth.

73. In a telephone system, the combination of a series of automatic switches, a talking circuit, means for successively operating said switches, and then releasing the same by controlling circuits including both sides of the talking circuit in series and means for supplying operating and talking current from the central station.

74. In a telephone system, a called line, a connector provided with an element having motion in one direction to select groups and in another direction to find the called line, release mechanism for restoring the connector to normal position, and a single line relay operative to control the motions of said element in both directions and the release of said connector.

75. In a telephone system, a plurality of trunks, an automatic trunking switch provided with an element having primary and secondary motion to find an idle trunk, and a single line relay operative to control the

primary motion and start the secondary motion.

76. In a telephone system, a plurality of trunks, an automatic trunking switch provided with line wipers having primary and secondary motion to find an idle trunk, and a single line relay operative to control the primary motion and start the secondary motion.

77. In a telephone system, a plurality of groups of lines including a called line, a connector provided with line wipers having primary and secondary motion to find the groups and the called line of groups, and a single line relay operative to control the primary and secondary motion.

78. In a telephone system, the combination with groups of lines including a called line, a connector provided with an element having primary and secondary motion to find the group and then the called line of the group, release mechanism for restoring the connector to normal position, a single line relay operative to control the primary and secondary motion and the release of said connector, and means for controlling said relay over a metallic line circuit.

79. In a telephone system, the combination of a plurality of trunks, an automatic trunking switch provided with an element having primary and secondary motion to find an idle trunk, a single line relay operative to control the primary motion and start the secondary motion, and means for controlling said relay over a metallic line circuit.

80. In a telephone system, the combination of a plurality of trunks, an automatic trunking switch provided with line wipers having primary and secondary motion to find an idle trunk, a single line relay operative to control the primary motion and start the secondary motion, and means for controlling said relay over a metallic line circuit.

81. In a telephone system, the combination with a group of lines including a called line, a connector provided with line wipers having primary and secondary motion to find the group containing the called line and then the called line in the group, a single line relay operative to control the primary and secondary motion, and means for controlling said relay over a metallic line circuit.

82. An automatic telephone system including calling and called lines, first selectors, second selectors, connectors, means for adjusting said first selectors by impulses over the metallic circuit conductors of the calling line in series, and means for adjusting the selected second selectors and connectors by repeating the calling line impulses at the first selectors.

83. In a telephone exchange system, the combination of subscribers' telephone lines, automatic means for extending connection from a calling telephone line to a called telephone line including a wiper having primary and secondary motion, disconnecting or releasing means adapted to be operated by the opening of a telephone line, and means by which a subscriber when through talking opens his line to thereby operate the 10 said disconnecting or releasing means without grounding the line.

In testimony whereof I have affixed my signature.

EDWARD E. CLEMENT.
